CLAIM

The ornamental design for a camera mount, as shown and described.

DESCRIPTION

FIG. 1 is a top, rear, left perspective view of a camera mount. FIG. 2 is a top plan view of the camera mount shown in FIG. 1.

FIG. 3 is a left elevation view of the camera mount shown in FIG. 1.

FIG. 4 is a right elevation view of the camera mount shown in FIG. 1.

FIG. 5 is a rear elevation view of the camera mount shown in FIG. 1; and,

FIG. 6 is a front elevation view of the camera mount shown in FIG. 1.

Broken lines of equal length represent portions of the camera mount and form no part of the claimed design.

1 Claim, 6 Drawing Sheets

FIG. 1

FIG. 2
